UNITED STATES PATENT OFFICE.

FRANK M. DYKE, OF RAMONA, CALIFORNIA.

SUBSOILER ATTACHMENT FOR PLOWS.

Application filed December 6, 1920. Serial No. 428,588.

To all whom it may concern:

Be it known that I, FRANK M. DYKE, a citizen of the United States, residing at Ramona, in the county of San Diego and 5 State of California, have invented certain new and useful Subsoiler Attachments for Plows, of which the following is a specification.

My invention relates to an attachment for 10 plows for breaking the ground in the furrow behind the plow to serve as a subsoiler and the objects of my invention are: first, to provide an attachment which is applicable for and may be readily applied to any 15 plow now in use for breaking the ground below the sole of the plow; second, to provide an attachment of this class which is adjustable so that it may be regulated for different depths; third, to provide an attachment of 20 this class which is positioned so that it is out of the way when in use with any kind of a plow; fourth, to provide an attachment of this class which is easy to install and fifth, to provide an attachment of this class which 25 is very simple and economical of construction, durable, easy to operate, adjustable throughout and which will not readily deteriorate or get out of order.

With these and other objects in view as 30 will appear hereinafter my invention consists of certain novel features of construction, combination and arrangement of parts and portions as will be hereinafter described in detail and particularly set forth in the 35 appended claims, reference being had to the accompanying drawings and to the characters of reference thereon which form a part of this application in which:

Figure 1 is a side elevational view of an 40 ordinary wooden beam walking plow showing portions broken away to facilitate the illustration and showing my attachment positioned thereon ready for use; Fig. 2 is an enlarged fragmentary detailed view of 45 the upper end of the main vertical supporting member; Fig. 3 is an enlarged detailed view of the clamp and clevis members for supporting the beam of the attachment on the plow; Fig. 4 is a sectional view through 50 4-4 of Fig. 1, on an enlarged scale; Fig. 5 is a view similar to that of Fig. 1, showing the attachment in connection with a steel beam walking plow, the position of the attachment being slightly modified from that 55 of Fig. 1.

Similar characters of reference refer to

similar parts and portions throughout the several views of the drawings.

The attachment shoe 1, beam 2, U bolt member 3, clip 4, clevis 5, front end support 60 6, clip 7 and spring 8 constitute the principal parts and portions of my attachment.

The shoe member 1 may be of any kind or character for the purpose of breaking up the ground in the furrow below the sole of 65 the plow and is secured to the beam 2. This beam 2 is preferably a metallic beam about two and one-half by five-eighths of an inch in cross section, shaped as shown best in Figs. 1 and 5 of the drawings. It is provided intermediate its ends with a plurality of spaced holes 2^a which are adapted for the reception of bolt 5^a of the clevis 5. This clevis 5 is pivotally mounted in a hole in the lug 4^a which extends upwardly on the clip 70 member 4. The main portion of this clip member 4 is provided with holes in opposite ends adapted for a U bolt 3 which is adapted to pass around the bar A which is a conventional bar for supporting the landside and 75 moldboard of the plow and on this bolt 3 are provided nuts 3^a, thus providing means for securing the clamp, consisting of the U bolt 3 and clip 4 securely on the member A and the clevis being pivotally mounted therein 80 permits the slight shifting movement of the beam relatively to the member 4 and the plurality of holes in the beam provides for adjustment of the beam 2 on the member 4. The front end of the beam is provided with 85 a plurality of holes 2^b over which is pivotally mounted the bifurcated end of the supporting member 6 which is also provided with a plurality of holes 6^a, thus providing 90 for the vertical and longitudinal adjustment 95 of the end of the beam, the two being held in their relative position by means of a bolt 6^b. The upper end of this supporting member 6 is shiftably mounted in a clip member 7 secured on the side of the beam of the plow 100 as shown best in Fig. 1 or on the brace between the handle and the beam as shown in Fig. 5. This clip member 7 is provided with teeth 7^a adapted for the teeth 6^c on the member 6 and mounted on the opposite side of the member 6 from the teeth 6^c is a spring 105 8 adapted to hold the teeth in engagement with the teeth 7^a on the clip 7, it being here noted that the pressure is ordinarily downward on the front end of the beam 2 when in use and at the clevis it is upwardly. The upper end of this supporting member 6 is 110

preferably provided with a knob to facilitate its support for movement relatively to said clip 7 for adjustment for the depth of the shoe member 1 in the ground in the furrow 5 behind the plow.

Though I have shown and described a particular construction, combination and arrangement of parts and portions and certain modifications thereof I do not wish to be 10 limited to this particular construction, combination and arrangement nor to the modifications thereof but desire to include in the purview of my invention the construction, combination and arrangement substantially 15 as set forth in the appended claims.

It is obvious that with this construction, there is provided an attachment which may be used with plows of different kinds and character for breaking up the ground behind the plow in the furrow below the sole of the plow; that the attachment is so constructed that it may be adjusted for different depths; that it may be clamped to the support A in the position desired for the 20 best results by securing the clamp formed by the U bolt 3 and clip 4 to said support A and the clevis will hold the beam from raising but will permit slight movement; and that the front end of the beam is rigidly 25 supported so that it may be adjusted for regulating the depth of the plow.

Having thus described my invention what I claim as new and desire to secure by Letters Patent is:

35 1. In an attachment of the class described, the combination with a plow, of a beam provided with a digging member, a clamp member secured to the plow, a clevis member pivotally connected to said clamp member

and connecting with said beam intermediate 40 its ends and a supporting member mounted on the plow adapted to support the normally front end of said beam.

2. In an attachment of the class described, the combination with a plow, of a beam provided with a digging member, a clamp member secured to the plow, a clevis member pivotally connected to said clamp member and connecting with said beam intermediate its ends, a supporting member mounted on the plow adapted to support the normally front end of said beam and means for adjusting said supporting member on said plow whereby the front end of said beam may be raised or lowered for regulating the depth of the 55 digging end of the beam.

3. In an attachment of the class described, the combination with a plow, of a beam provided with a digging member, a clamp member secured to the plow, a clevis member pivotally connected to said clamp member and connecting with said beam intermediate its ends, a supporting member mounted on the plow adapted to support the normally front end of said beam, means for adjusting 60 said supporting member on said plow whereby the front end of said beam may be raised or lowered for regulating the depth of the digging end of the beam comprising a clip member secured to the plow provided with a 65 spring in one side and teeth in the other adapted to engage the teeth on said supporting member.

In testimony whereof I have hereunto set my hand at San Diego, California, this 75 27th day of November, 1920.

FRANK M. DYKE.
